(21) Appl. No.: **29/164,001**

CLAIM

(22) Filed: **Jul. 16, 2002**

The ornamental design for a watch casing and portion of a strap, as shown and described.

(51) LOC (7) Cl. **10-02**

DESCRIPTION

(52) U.S. Cl. **D10/30**

FIG. 1 is a top plan view of a watch casing and portion of a strap showing my new design;

(58) Field of Search D10/1-40, 122-132; 368/280-282, 276-277, 28-30, 285, 239-242, 243-249, 82-84, 41-44

FIG. 2 is a left side elevational view thereof;

(56) **References Cited**

FIG. 3 is a right side elevational view thereof;

U.S. PATENT DOCUMENTS

FIG. 4 is a first end elevational view thereof;

D328,870 S * 8/1992 Chodat D10/30

FIG. 5 is a second end elevational view thereof; and,

D365,282 S * 12/1995 Chodat D10/30

FIG. 6 is a bottom plan view.

D394,400 S * 5/1998 Iwamoto D10/30

The speckled dots are intended to illustrate a contrast in

D407,027 S * 3/1999 Kubo et al. D10/30

color and/or material used to construct and illustrate the

D407,329 S * 3/1999 Kawashima et al. D10/30

claimed invention. The fact that the drawings illustrate dots,

D423,947 S * 5/2000 Sugisawa et al. D10/30

in and of itself, is not material to the invention.

D426,779 S * 6/2000 Hatsuki D10/30
